[57] CLAIM

The ornamental design for a front face of a vehicle wheel, as shown and described.

DESCRIPTION

FIG. 1 is a front view of a front face of a vehicle wheel according to my novel design but the bolt, hub and valve holes are not part of the claimed design;

FIG. 2 is a front perspective view of a front face of a vehicle wheel according to my novel design, and with the broken line showing for illustrative purposes only and forming no part of the claimed design;

FIG. 3 is a side perspective view of a vehicle wheel according to my novel design; and,

FIG. 4 is another side perspective view of a vehicle wheel rotated from the position shown in FIG. 3 according to my novel design.
